(No Model.)

F. R. COLVIN.
TELEPHONE SYSTEM.

No. 552,823.

Patented Jan. 7, 1896.

UNITED STATES PATENT OFFICE.

FRANK R. COLVIN, OF NEW YORK, N. Y., ASSIGNOR TO THE INTERIOR
TELEPHONE COMPANY, OF SAME PLACE.

TELEPHONE SYSTEM.

SPECIFICATION forming part of Letters Patent No. 552,823, dated January 7, 1896.

Application filed February 2, 1895. Serial No. 537,089. (No model.)

To all whom it may concern:

Be it known that I, FRANK R. COLVIN, a citizen of the United States, residing in the city, county, and State of New York, have invented certain new and useful Improvements in Telephone Systems, of which the following is a specification.

This invention relates to telephone systems, its object being to provide a simple and effective central-office apparatus for coupling subscribers' circuits and permitting the central-office operator to hear and converse with both connected subscribers without disturbing the relations of their circuits.

With this end in view I provide in each connecting-cord used to couple the subscribers' circuits an induction-coil, one winding of which is in series with the cord and the other winding of which is in a local circuit including a battery-transmitter, a battery and a telephone-receiver. With this provision the central operator may at all times hear and be heard by the subscribers without manipulating switches as has heretofore been customary.

The novelty of the invention will be more fully explained hereinafter and will be definitely indicated in the claims.

In the accompanying drawing is diagrammatically shown a system embodying my improvements.

A B C represent three subscribers' stations, the first having a private line connecting it with central office, and the other two having a common line connecting them therewith.

The drawing illustrates a system equipped with metallic circuits, though the main features of the invention may be carried out with grounded circuits. At each station a magneto-bell 1 ^{1a} ^{1b} is normally included in circuit, and switches 2 ^{2a}, &c., are provided for cutting it out and including a battery-transmitter 3 and receiver 4. The switch is provided with a hook to support the telephone and is so arranged that when shifted to its talking position it will not support the telephone, thus insuring a proper restoration of the circuits when conversation is concluded. This construction is fully described and claimed in a patent granted to me March 27, 1894, No. 517,263.

In a normally-open ground at each station is a key 5 ^{5a}, &c., by which a battery 6 at central station may be thrown into circuit through annunciators or indicators 7 ^{7a} in parallel relation to each other. A connecting-cord or plurality of such cords is provided at central office by which the several subscribers' circuits may be interconnected. These cords, one pair of which is shown, terminate in switch-plugs 8 9, comprising two metallic surfaces or cylinders insulated from one another and mounted on a common support. The inner cylinder is adapted to engage a pin 10 ^{10a} of a jack-switch, and the outer one a spring-contact 11 ^{11a} of said switch. Thus when the two plugs are inserted in the switches corresponding to two subscribers' circuits the subscribers' instruments will be in circuit with one another. A battery 12 is inserted in that side of the cord which when the plug is in circuit will be disconnected from the annunciator. In series relation with the other side of each cord is one winding of an induction-coil 13, the other winding of which is in a local circuit 14 including a battery, carbon transmitter and receiver. The ratio of transformation of the induction-coil is preferably 1:1. Each central operator is also provided with a calling-plug 15 connected or adapted to be connected with a magneto-call generator 16 and an answering-circuit including a battery, a transmitter and a receiver, as shown in circuit 17. Certain features of the system herein described are claimed in another application filed by me. The feature of novelty to which claim is made in the present application is the induction-coil 13 and its relation to the connecting-cord and listening-circuit by which the central-office operator is in continuous communicating relation to both subscribers during transmission. As heretofore organized the listening-telephone is placed in parallel relation to the talking-circuit, requiring a branch of very high resistance to prevent a diversion of too much current and reduction of the loudness of transmission at the distant stations. Obviously, with my organization, the induction-coil being in series may be made of very low resistance and cannot divert any current from the distant in-

struments. The quality or loudness of transmission is therefore unaffected and is the same for all instruments in circuit. Moreover, the difference of resistance of two connected circuits, by reason of difference of length or conductivity or different local atmospheric or line conditions, cannot render one instrument feeble, as might be the case where the central-office listening-receiver is in a branch circuit across the line.

Having thus described my invention, what I claim as new, and desire to secure by Letters Patent, is—

1. The combination with a number of telephone lines extending to the central station, of a cord connector for connecting the circuits together for conversation, an induction coil having the secondary connected in series with said cord connector, and a telephone transmitter and receiver in circuit with the primary of said induction coil, whereby the

telephone set may remain continuously in operative connection with the cord connector substantially as described.

2. A telephone system comprising a plurality of subscribers' circuits connecting with a central office, battery transmitters at the several subscribers' stations, a connecting cord or cords at central office, a battery for furnishing transmitting current in circuit with said cord, and an induction coil having one winding in series with the cord and the other winding in a local listening circuit including transmitting and receiving apparatus.

In testimony whereof I have hereunto subscribed my name this 31st day of January, A. D. 1895.

FRANK R. COLVIN.
